PUMP UNLOADING MECHANISM

Nelson E. Brigham, Kearny, N. J., and Joseph E. Holveck, Crafton, Pa., assignors to Worthington Pump and Machinery Corporation, Harrison, N. J., a corporation of Delaware

Application October 5, 1940, Serial No. 359,874

17 Claims. (Cl. 103—37)

This invention relates to a loading and unloading mechanism for positive displacement pumps, and an object of the invention is to provide a simple, positive acting means for controlling a positive displacement or reciprocating pump, of any type, which will provide synchronization of all of the cylinders of the pump in unloading and loading, regardless of the point in pump revolution when the control functions.

In practically all pumping applications involving a pressure fluid for operating hydraulic machinery the demand for fluid power medium has any of a number of flow conditions, all of which require intermittent operation of the pump. Consequently the pump operates loaded to full capacity for a given time, and at zero capacity for another given time. The relation between the length of loaded and unloaded time cycles depends upon the type of rate of flow, the flow demand at a given time, the accumulator capacity, and the capacity of the pump.

The present invention provides a synchronized loading and unloading mechanism capable of meeting any and all demand conditions, in an installation as above referred to, where power driven reciprocating pumps are employed. It involves a control for such pumps which, when operating continuously and at constant speed, provides a quick but gradual decelerating fluid flow from full to zero flow in not more than one-half revolution of the pump, and a quick but gradual accelerating fluid delivery from zero to full flow in not more than one-half revolution of the pump, i. e. synchronized unloading and loading.

The discharge flow from a positive displacement multi-plunger reciprocating pump is made up of a consecutive series of equal pulsations, or plunger displacements, comprising a smooth resultant delivery. Each plunger displacement, due to crank action, is forced into the pressure line with an increasing rate of flow from zero to maximum, and continuing with a corresponding diminishing rate of flow from maximum to zero through 180 degrees of crank motion.

Placing interference under the suction valve during the suction stroke causes the pump to unload in such a manner that the interruption of the pump action at the end of a loaded cycle is a gradual deceleration of fluid delivery and power input from full to zero, coinciding with the diminishing rate of flow of the last plunger displacement into the pressure line. This basic and inherent characteristic eliminates shock.

To bring this about, the suction valves of each

plunger are kept open by an interference placed under each valve during the suction stroke of each plunger, causing the valves to become inoperative and resulting in each plunger remaining unloaded at the end of its preceding discharge stroke. During the unloading cycle, the pump discharge valves hold the pressure fluid, and each suction displacement is returned back into the suction chamber.

10 During the unloading cycle, the pump operates only on suction pressure, and no work is being done by the pump. The power required when unloaded need only be sufficient to overcome the mechanical friction of the pump.

15 Removing interference from under the suction valve causes the pump to load in such a manner that the resumption of the pump action at the beginning of a loaded cycle is a gradual acceleration of fluid delivery and power input from zero to full, coinciding with the increasing rate of flow of the first plunger displacement into the pressure line. This basic and inherent characteristic eliminates shock.

20 To bring this about, the interference is removed from under each suction valve during the suction stroke of each plunger, causing the valves to become operative, and resulting in each plunger being loaded at the beginning of its discharge stroke.

25 Other objects of the present invention are to provide a loading and unloading mechanism which will provide shockless unloading and loading of the pump, minimum power loss when the pump is unloaded, no loss of pressure fluid when the pump is unloaded, and one which eliminates shocks to and wear upon the equipment permitting the pump to be unloaded and loaded with any degree of frequency.

30 With these and other objects in view, as may appear from the accompanying specification, the invention consists of various features of construction and combination of parts, which will be first described in connection with the accompanying drawings, showing a pump unloading mechanism of the preferred form embodying the invention, and the features forming the invention will be specifically pointed out in the claims.

35 In the drawings:

40 Figure 1 is a top plan of the improved unloading and loading mechanism showing it in connection with a pump.

45 Figure 2 is a side elevation of a pump showing the improved unloading and loading mechanism applied thereto.

50 Figure 3 is a fragmentary longitudinal section

through a pump showing parts of the unloading and loading mechanism applied, and taken on the line 3—3 of Figure 1.

Figure 4 is a top plan of the distributor control mechanism.

Figure 5 is a vertical section through the distributor control mechanism taken on the line 5—5 of Figure 4.

Figure 6 is a section through one of the pump valve actuating mechanisms showing it in connection with one of the suction valves of the pump, and taken on the line 6—6 of Figure 3.

Figure 7 is a side elevation of a cam employed in the control mechanism.

Figure 8 is a section taken on the line 8—8 of Figure 7.

Figure 9 is a lay-cut development of the cam shown in Figure 7.

Figure 10 is a perspective view of a control switch employed in the control mechanism.

Figure 11 is a vertical section through the switch shown in Figure 10.

Figure 12 is a perspective view of a pressure fluid distributor valve and its operating mechanism which controls the delivery of operating pressure fluid to the pump valve actuating mechanism.

Figure 13 is a diagrammatic view of the electrical circuits embodied in the control and distributor mechanism of the device.

Referring more particularly to the drawings, a double-acting positive-displacement pump of the reciprocating type is shown in Figures 1 and 2 of the drawings, embodying cylinders 1, each having opposed bores 2 and 3 therein in which the plunger pistons 4 and 5 reciprocate.

The plungers 4 and 5 are reciprocated from any suitable type of prime mover (not shown) through the medium of the crank shaft 6, which is connected to the plungers by suitable connecting rods, guide rods and cross-heads 7, 8 and 9, in the usual manner of constructing pumps of this type.

Each of the cylinders is provided with a fluid inlet passage 10, opening through inlet valve structures 11 into the bores 2 and 3 respectively. The cylinders are each provided with approved types of discharge valves 12. The present invention does not relate to any specific type of construction of pump but embraces a synchronized loading and unloading mechanism for automatically controlling the loading and unloading of a pump in response to pressure fluid demand.

The pump cylinders are unloaded by the holding open of the suction valves 11, and are loaded by the release of the suction valves from the unloading or holding open mechanism, so as to permit them to operate in their usual manner.

The valve operating mechanism for holding the suction or inlet valves open to unload the pump is shown in detail in Figure 6 of the drawings, and includes a rod 14 extending into the cylinder 1 and not attached to, but engaging the skirt 15 of the suction valve 11. The rod 14 is attached to a piston 16, mounted for reciprocatory movement in a cylinder 17. A stem 18 engages the piston structure 16 and is urged upwardly or inwardly to move the piston 16 upwardly in the cylinder 17 by a spring 19 so that when the piston 16 is relieved from the action of pressure fluid against its inner side the spring 19 will urge the piston inwardly or upwardly, causing the pin 14 to engage the valve 11 and move it inwardly against the tension of its set-

ting spring 20 so as to hold the valve 11 open, consequently causing the pump to operate unloaded. The cylinder 17 has an inlet 21 thereto for pressure fluid. Pressure fluid, entering the cylinder 17, forces the piston 16 outwardly against the tension of the spring 19 and moves the rod 14 out of position for holding the valve 11 open, thereby permitting the inlet or suction valve 11 to operate in its normal manner and the pump to operate loaded.

Pressure fluid for actuating the piston 16 is provided from any outside source (not shown), such as the compressed air line or system of a plant in which the pump is employed. Distribution of pressure fluid to the cylinders 17 is controlled by a series of solenoid actuated, three-way valve structures 22, which are of any approved construction that may be purchased upon the open market. These three-way valve structures are constructed so that when their solenoid structures, generically indicated at 23, are energized, the valves will be in position to permit the flow of pressure fluid from the supply source to the cylinders 17, permitting the pump cylinder controlled by the respective solenoid valve to be loaded. When the solenoid 23 is de-energized, the three-way valve structure 22 will permit the bleeding of the pressure fluid from the cylinder 17 to allow the spring 19 to act to unload the respective pump cylinder. As shown in Figure 1 of the drawings, one of the solenoid actuated three-way valve structures is provided for each of the suction valves of the pump. As previously stated, the pressure fluid for actuating the pistons 16 may be derived from any suitable source, and flows to the battery of three-way valve structures 22 through a supply line 24.

The energizing of the solenoids 23 of the various three-way valve structures 22 is controlled by the distributor structure 30, which is operated from the crank shaft 6 of the pump by a suitable power transmission mechanism, indicated at 31.

The distributor control mechanism 30 includes a suitable housing 33, in which are mounted a plurality of switch structures 34, one for each of the solenoid actuated three-way valves 22. These switch structures are of an approved type which may be purchased upon the open market, but they are, however, shown in detail in Figures 10 and 11 of the drawings.

The switch structures 34 are connected in circuit with the solenoids 23, and each includes a rocker arm 35 controlling the opening and closing of the circuit through the switch and consequently through the solenoid 23 connected to the respective switch 34. The rocker arms 35 are each connected to a pivotally mounted actuating arm 36, which arm is positioned exteriorly of the casing 37 of the switch and has a cam engaging roller 38 on its outer free end. The actuating arms 36 are pivotally supported from the housing 37 and when in an upward position as shown in solid lines in Figure 5 of the drawings actuate the switch structures to close the circuit through the solenoids 23, to in turn operate the three-way valves 22 permitting the pressure fluid to be delivered to the cylinders 17 for operating the pistons 16, to permit the pump to operate in loaded condition.

The distributor control 30 has a solenoid 40, of approved construction, mounted therein which is connected in circuit with a pressure governor, (not shown), or limit switches, (not shown), which may be associated with the pump structure.

A plunger shaft 41 is connected to the core of

the solenoid 40 and moves vertically in suitable bearings 42 and 43, upon the energizing or de-energizing of the solenoid. That is, when the solenoid is energized, and the core 44 thereof is drawn upwardly, the shaft 41 will move upwardly; and upon de-energizing of the solenoid 40 the core 44 and shaft 41 will drop or move downwardly, such downward movement being augmented by means of the spring 45. The lower end of the shaft 41 extends into a socket or pocket 45', which receives oil through an opening 46. The shaft 41 is provided with a longitudinal bore 47 and with lateral extending openings 48, so that when the shaft 41 moves downwardly lubricating oil will be forced upwardly through the bore 47 of the shaft and through the openings 48 for lubricating the working parts of the control. The socket 45', containing oil, also acts as a dash-pot to cushion the downward movement of the shaft 41 and the mechanism carried thereby.

The shaft 41 has a cam structure 49 rotatably mounted thereon and held in place on the shaft by means of the collar 50 and the shoulder 51 so that the cam will move vertically with movement of the shaft. The cam 49 has a pinion 52 keyed thereto which meshes with a worm gear 53 mounted on a suitable shaft 54. The shaft 54 is connected in any suitable manner with the transmission mechanism 31 so that the worm gear 53, and consequently the cam 49, will be rotated in synchronism with the rotation of the crank shaft 6 of the pump structure.

The cam 49 has upper and lower annular flanges 55 and 56, respectively, formed thereon, providing facing cam surfaces 57 and 58, each of which has a riser 59 formed thereon at the proper point about its circumference. The risers 59 are provided for engagement with the rollers 38 to actuate the pivoted switch operating arms 36 during the suction stroke of the respective plungers.

When the solenoid 40 is energized and the shaft 41 drawn upwardly, the riser 59 on the lower cam 58 will engage the rollers 38 at the proper times during the rotation of the cam 49 to move the levers 36 upwardly and close the circuits through the various solenoids 23 which are connected in circuit with the respective switches 34, during the suction stroke of their respective plungers. As each solenoid 23 is energized in its proper sequence, the pump cylinder with which it and its three-way valve are associated will be loaded in proper synchronized relation with the operation of the plungers of the respective pump cylinders during the suction stroke, owing to the synchronizing connection between the cam 49 and the crank shaft 6 of the pump.

When the solenoid 40 is de-energized the shaft 41, and consequently the cam 49, will move downwardly, moving the risers of the cam surface 57 into position for intermittent engagement with the rollers 36 and thus, at the proper points during rotation of the cam 49, the levers 36 of the various switches 34 will be moved downwardly into the dotted line position shown in Figure 5 of the drawings, thus breaking the circuit through the switches 34 and their respective solenoids 23, in proper synchronized sequence with the operations of the plungers of the pump so as to relieve the pistons 16 of the pressure of the pressure fluid and permit such pressure fluid to bleed out of the cylinders 17 during the suction stroke. When the pressure fluid bleeds

out of the cylinders 17 the springs will act to move the piston 16 and rod 14 upwardly during the suction stroke, thereby preventing the suction valves of the various pump cylinders from functioning and causing the pump cylinders to operate in an unloaded condition, thus unloading the pump in synchronization with the rotation of the crank shaft 6; that is, unloading the pump in synchronization with the movement of the plungers at the end of each discharge stroke.

As previously stated, the energizing and de-energizing of the solenoid 40 may be controlled by a pressure governor, limit switches, or any other suitable control apparatus, depending upon the use to which the pump is to be put, so as to load and unload the pump in accordance with the load demand, at specified time intervals or to suit any of a number of conditions which may exist in various types of installations in which the pump is employed. The present invention does not embody any specific control means for controlling this action.

It will be understood that the invention is not to be limited to the specific construction or arrangement of parts shown, but that they may be widely modified within the invention defined by the claims.

What is claimed is:

1. In a pump loading and unloading mechanism, in combination with a pump including a cylinder and a reciprocating plunger therein, of a valve for controlling the loading and unloading of the cylinder, a pressure actuated member for operating said valve, electrically operated means controlling delivery of pressure fluid to said pressure actuated member, a control member controlling energizing of said electrically operated means, and means connecting said control member to said plunger for synchronized operation therewith for timing the valve actuating operation of said pressure actuated member.

2. In a pump loading and unloading mechanism, in combination with a pump including a cylinder and a reciprocating plunger therefor, and an intake valve for said cylinder, of a pressure actuated member acting upon said intake valve to control unloading of the pump, electrically operated means controlling delivery of actuating pressure fluid to said member, and a control member connected to and actuated in synchronism with said plunger for controlling energizing of said electrically operated means.

3. In a pump loading and unloading mechanism, the combination with a pump including a cylinder and a plunger therein, and an intake valve for said cylinder, of a pressure actuated member normally holding said intake valve in cylinder unloading position and operated by pressure fluid to permit seating of said suction valve to load said pump, a valve controlling delivery of pressure fluid to said pressure actuated member, electrical means for actuating said valve, means for moving said pressure actuated member into valve unseating position upon the release of pressure fluid from said pressure actuated means, a distributor controlling the energizing of said electrical means for controlling the delivery of pressure fluid to and the release of pressure fluid from said pressure actuated member, and means connecting said distributor to said plunger for synchronized operation therewith.

4. In a loading and unloading mechanism for pumps, the combination with a pump including

cylinders, plungers therein, intake valves for said cylinders, of pressure actuated means for holding said intake valves open to unload the pump and movable out of valve holding position to permit loading of the pump, valves controlling the delivery of pressure fluid to said pressure actuated means, a distributor including an actuating cam, means actuated by said cam for controlling operation of said valves, and means for operating said cam in synchronism with the pump plungers.

5. In a loading and unloading mechanism for pumps, the combination with a pump including cylinders, plungers therein, and intake valves for said cylinders, of pressure actuated means for holding said intake valves open to unload the pump and movable out of valve holding position to permit loading of the pump, valves controlling the delivery of pressure fluid to said pressure actuated means, a distributor including an actuating cam, means actuated by said cam for controlling operation of said valves, a crank shaft for operating said pump plungers, and means for rotating said cam connected to said crank shaft whereby said cam will be operated in synchronism with the pump plungers for timing the valve operating operations of said pressure actuated members.

6. In a loading and unloading mechanism for pumps, the combination with a pump including cylinders, plungers therein, and intake valves for said cylinders, of pressure actuated means for holding said intake valves open to unload the pump and movable out of valve holding position to permit loading of the pump, valves controlling the delivery of pressure fluid to said pressure actuated means, solenoids for operating said valves, a distributor including a cam, switches actuated by the cam for controlling energizing of said solenoids, a crank shaft for operating said pump plungers, and means for rotating said cam connected to said crank shaft for rotating the cam in synchronism with movement of the pump plungers.

7. In a pump loading and unloading mechanism, the combination with a pump including a cylinder and a reciprocating plunger therein, of a valve for controlling the loading and unloading of the cylinder, a pressure actuated member for operating said valve, a valve controlling the delivery of pressure fluid to said pressure actuated means, a distributor including a cam, means actuated by said cam for controlling operation of said control valve, and means for operating said cam in synchronism with movement of said pump plunger.

8. In a loading and unloading mechanism for pumps, the combination with a pump including cylinders, plungers therein, and intake valves for said cylinders, of pressure actuated means for holding said intake valves open to unload the pump and movable out of valve holding position to permit loading of the pump, valves controlling the delivery of pressure fluid to said pressure actuated means, solenoids for operating said valves, a distributor including a cam, means for rotating said cam, switches carried by said distributor for controlling energizing of said solenoids, and means for moving said cam in one direction to operate the switches for energizing said solenoids and in an opposite direction to operate the switches to de-energize the solenoids.

9. In a loading and unloading mechanism for pumps, the combination with a pump including cylinders, plungers therein, and intake valves

for said cylinders, of pressure actuated means for holding said intake valves open to unload the pump and movable out of valve holding position to permit loading of the pump, valves controlling the delivery of pressure fluid to said pressure actuated means, solenoids for operating said valves, a distributor including a cam, means for rotating said cam, switches carried by said distributor for controlling energizing of said solenoids, means for moving said cam in one direction to operate the switches for energizing said solenoids and in an opposite direction to operate the switches to de-energize the solenoids, a crank shaft for operating said pump plungers, said cam rotating means connected to said crank shaft for rotating the cam in synchronism with the crank shaft.

10. In a loading and unloading mechanism for pumps, the combination with a pump including cylinders, plungers therein, and intake valves for said cylinders, of pressure actuated means for holding said intake valves open to unload the pump and movable out of valve holding position to permit loading of the pump, valves controlling the delivery of pressure fluid to said pressure actuated means, solenoids for operating said valves, a distributor including a cam, means for rotating said cam, switches carried by said distributor for controlling energizing of said solenoids, a solenoid for moving said cam into switch actuating position to load the pump upon energizing thereof, and means for moving the cam in a reverse direction upon de-energizing of the cam moving solenoid to actuate the switches to unload the pump.

11. In a loading and unloading mechanism for pumps, the combination with a pump including cylinders, plungers therein, and intake valves for said cylinders, of pressure actuated means for holding said intake valves open to unload the pump and movable out of valve holding position to permit loading of the pump, valves controlling the delivery of pressure fluid to said pressure actuated means, solenoids for operating said valves, a distributor including a cam, switches actuated by the cam for controlling energizing of said solenoids, a cam actuating solenoid for moving said cam into switch actuating position to load the pump upon energizing of said cam actuating solenoid, means for moving the cam in a reverse direction upon de-energizing of the cam actuating solenoid to actuate said switches to unload the pump, and means for rotating said cam in synchronism with the movement of the pump plungers whereby the pump will be loaded and unloaded in synchronism with movement of the pump plungers.

12. In a pump loading and unloading mechanism, in combination with a pump including a cylinder and a reciprocating plunger therein, a crank shaft for reciprocating said plunger, a suction valve for said cylinder, obstruction means for movement into or out of engagement with said suction valve to unload or load the pump, electrically operated means controlling movement of said obstruction means, a control member controlling energizing of said electrically operated means, and means connecting said control member and crank shaft for timing the operation of said obstruction means, whereby it will only be operated at predetermined points during the suction stroke of said plunger.

13. In a pump loading and unloading mechanism, in combination with a pump including a cylinder and a reciprocating plunger therein, a

crank shaft for reciprocating said plunger, a suction valve for said cylinder, obstruction means for movement into or out of engagement with said suction valve to unload or load the pump, electrically operated means controlling movement of said obstruction means, a control member, said control member including an actuating cam for controlling energizing of said electrically operated means, means for rotating said cam in synchronism with rotation of said crank shaft, said cam constructed and arranged whereby energizing and de-energizing of said electrical control means will only occur at predetermined points during the suction stroke of said plunger.

14. In a pump loading and unloading mechanism, in combination with a pump including a cylinder and a reciprocating plunger therein, a crank shaft for reciprocating said plunger, a suction valve for said cylinder, obstruction means for movement into or out of engagement with said suction valve to unload or load the pump, electrically operated means controlling movement of said obstruction means, a control member, said control member including an actuating cam for controlling energizing of said electrically operated means, means for rotating said cam in synchronism with rotation of said crank shaft, said cam constructed and arranged whereby energizing and de-energizing of said electrical control means will only occur at predetermined points during the suction stroke of said plunger, means for moving said cam in one direction whereby the electrical means will be energized, means for removing the obstruction means from engagement with the suction valve upon energizing of the electrical means, said cam movable in an opposite direction to de-energize the electrical means, and means for moving the obstruction means into engagement with the suction valve upon de-energizing of the electrical means. 20

15. In a loading and unloading mechanism for pumps, the combination with a pump including cylinders and plungers therein, of pressure actuated means for controlling loading and unloading of the pump, valves controlling the de- 40

livery of pressure fluid to said pressure actuated means, solenoids for operating said valves, a distributor including a cam, means for rotating said cam, switches carried by said distributor for controlling energizing of said solenoids, means for moving said cam in one direction to operate the switches for energizing said solenoids and in an opposite direction to de-energize the solenoids, and mechanical means connecting said cam and plungers for operating the cams in synchronism with the plungers.

16. In a loading and unloading mechanism for pumps, the combination with a pump including cylinders and plungers therein, of pressure actuated means for controlling the loading and unloading of the pump, valves controlling the delivery of pressure fluid to said pressure actuated means, solenoids for operating said valves, a distributor including a cam, means for rotating said cam, switches carried by said distributor for controlling energizing of the solenoids, a solenoid for moving said cam into switch actuating position to load the pump upon energizing thereof, and means operative upon de-energizing of said cam moving solenoid to unload the pump. 25

17. In a pump loading and unloading mechanism, in combination with a pump including a cylinder and reciprocating plungers therein, a suction valve for said cylinder, obstruction means for movement into or out of engagement with said suction valve to unload or load the pump, electrically operated means controlling movement of said obstruction means, a control member controlling energizing of said electrically operated means, mechanical means connecting said control member and plungers for timing the operation of said obstruction means whereby the obstruction means will be operated only at predetermined points during the suction stroke of said plungers, and means operative upon de-energizing of said electrically operated means to unload the pump. 30
